Primary Examiner — Richard Kearney(74) *Attorney, Agent, or Firm* — McCormick, Paulting & Huber PLLC(57) **CLAIM**

The ornamental design for a lamp, as shown and described.

DESCRIPTION

1. Lamp
- 1.1 : Perspective
- 1.2 : Perspective
- 1.3 : Perspective
- 1.4 : Top
- 1.5 : Bottom
- 1.6 : Front
- 1.7 : Left
- 1.8 : Right

In Figure 1.3 the lamp is shown with the band dismounted; the broken lines in the drawings illustrate break lines which form no part of the claimed design; the break lines in reproductions indicate that the appearance of any portion of the lamp between the break lines forms no part of the claimed design.

1 Claim, 8 Drawing Sheets(56)
